(57) **CLAIM**

The ornamental design for a coin storage and displaying assembly, as shown and described.

DESCRIPTION

FIG. 1 is a front elevated view of a coin storage and displaying assembly showing my new design;

FIG. 2 is a rear elevated view of the coin storage and displaying assembly;

FIG. 3 is a side elevated view of the coin storage and displaying assembly;

FIG. 4 is a top plan view of the coin storage and displaying assembly;

FIG. 5 is a bottom plan view of the coin storage and displaying assembly; and,

FIG. 6 is a top perspective view of the coin storage and displaying assembly.

The broken line showing of lettering illustrates environmental subject matter, which forms no part of the claimed design.
